[57] **CLAIM**

The ornamental design for a bug catcher to be used on the side of a pool, as shown and described.

DESCRIPTION

FIG. 1 is a front, top and side perspective view of the bug catcher to be used on the side of a pool showing my new design;

FIG. 2 is a side elevational view, the opposed side being a mirror image thereof;

FIG. 3 is a top plan view thereof;

FIG. 4 is a bottom plan view thereof;

FIG. 5 is a front elevational view thereof; and,

FIG. 6 is a rear elevational view thereof.

The cross-hatching in FIGS. 1 and 2 is fragmentarily shown for convenience of illustration, it being understood that the cross-hatching is uniformly continuous over the surface on which it appears.
